(57) **CLAIM**

The ornamental design for an overshoe, as shown and described.

DESCRIPTION

FIG. 1 is a front and side perspective view of an overshoe, showing my new design;

FIG. 2 is a left side view of the overshoe;

FIG. 3 is a right side view thereof;

FIG. 4 is a top plan view thereof;

FIG. 5 is a bottom plan view thereof;

FIG. 6 is a front elevational view thereof;

FIG. 7 is a rear elevational view thereof; and,

FIG. 8 is a cross-sectional view of an overshoe taken along line 8-8 of FIG. 4.

The broken lines illustrate unclaimed environmental structure.
